(Model.)

J. G. KRICHBAUM.
Hasp Lock.

No. 240,911.

Patented May 3, 1881.

UNITED STATES PATENT OFFICE.

JOHN G. KRICHBAUM, OF YOUNGSTOWN, OHIO.

HASP-LOCK.

SPECIFICATION forming part of Letters Patent No. 240,911, dated May 3, 1881.

Application filed October 27, 1880. (Model.)

To all whom it may concern:

Be it known that I, JOHN G. KRICHBAUM, a citizen of the United States of America, residing at Youngstown, in the county of Mahoning and State of Ohio, have invented certain new and useful Improvements in Hasp-Locks; and I do hereby declare the following to be a full, clear, and exact description of the invention, such as will enable others skilled in the art to which it appertains to make and use the same, reference being had to the accompanying drawings, and to the letters or figures of reference marked thereon, which form a part of this specification.

This invention relates to that class of locks the case of which is combined with and forms a part of a hasp, said hasp and lock being adapted to engage with a stud or staple, and obviate the necessity of using a padlock which can be detached and mislaid or lost.

The invention consists in the combining of the following parts, the novel features of which will be more particularly set forth in the claim at the close of this specification: A lock-case the back plate of which is extended on one side to form a hasp; a bent bolt-plate having a notched flange or web on which the key operates to move the bolt-plate back and forth; a spring-actuated tumbler for locking the bolt-plate at either extremity of its range of motion; a spring for moving the bolt-plate in one direction; an arm or trigger pivoted within the lock-case and extending to the outside thereof, by which the bolt-plate, when the bolt is retracted, can be freed from the tumbler and the lock locked without using the key.

In the annexed drawings, Figure 1 is a perspective view of a chest provided with one of my improved hasp-locks. Fig. 2 is a plan of my hasp-lock, the face-plate being removed and reversed. Fig. 3 is a similar view, showing the bolt retracted. Fig. 4 is a plan, showing the bolt-plate. Fig. 5 represents details of the tumbler. Fig. 6 is a view of the face-plate reversed. Fig. 7 is the key.

The same letters of reference are used in all the figures in the designation of identical parts.

The hasp A is formed from an extension of the back-plate B of the lock-case, said plate being provided with a slot for the reception of a staple, with which the bolt engages. This

hasp may be provided with a hinge-joint and secured to a door or other object by bolts or screws a, as shown; or it may be made in one rigid piece, provided with a hole near the end, 55 and secured with a staple in such manner as to admit of its being swung out away from the door.

The walls B' of the lock-case in this instance form a square, and are secured to the back-plate B by bolts, in the manner ordinarily practiced in the construction of such devices.

The face-plate B² of the lock is provided with the usual key-hole.

The bolt-plate D, extending entirely across the lock-case and provided at its ends with legs d, is seated within said case, its legs d fitting so closely to the sides of the case as to prevent wabbling of the plate when it is slid back and forth. One leg of this bolt-plate is provided 70 with a flange or web, D', having a notch, d', cut in its edge, and being also slotted at d², so that it can slide up and down on the post H, fixed to the back-plate of the lock. This flange is provided at its upper end with a post, d³, on 75 which is pivoted a tumbler, E, having a slot, e, provided on one edge with notches e' e². The tumbler E is provided at its free end with an arm, E', terminating near the face-plate of the lock with a spur and shoulder, as shown in Fig. 5. 80

On the post d³ is seated a bifurcated spring, E², one leg of which bears outwardly against one leg, d, of the bolt-plate D, while the other leg bears against the arm E' of tumbler E and tends to force the notched edge of the slot e in 85 said tumbler against the fixed post H, which projects up into said slot.

To the plate D is secured the bolt, in such position that it can be shot across the slot in the back-plate B of the lock through the staple I. 90

A spring, F, of any suitable form, is seated against the upper wall of the lock-case and acts to force the bolt-plate D down to the position it occupies when the lock is locked.

To the inner side of the face-plate B² is pivoted a trigger, G, curved as shown, its free end extending down through a slot in the lower wall of the lock-case. This trigger occupies the space between the shoulder of arm E' of tumbler E and the face-plate of the lock, and 100 engages with its convex edge the spur on said arm E', so that by moving the exterior end of

said trigger to one side the notch e^2 in slot e of tumbler E, when in engagement with post H, will be freed therefrom, thus permitting the plate D to be actuated by spring F, so as to 5 shoot the bolt through the staple I and lock the lock.

Having thus described my invention, what I claim as new is—

In a hasp-lock, the combination, substantially as before set forth, of the bolt-plate, the 10 spring for moving it in one direction, the tum-

bler pivoted to the bolt-plate, the fixed post for engaging the tumbler, and the trigger for freeing the tumbler from the post, so that the bolt can be shot by its spring.

In testimony whereof I affix my signature in presence of two witnesses.

JOHN GEORGE KRICHBAUM.

Witnesses:

ROBERT BURNSIDE,
ADDIS E. KNIGHT.
